ATTORNEYS

UNITED STATES PATENT OFFICE.

WALTER THOMAS, OF PALATKA, FLORIDA.

TRICK-SWORD.

SPECIFICATION forming part of Letters Patent No. 714,534, dated November 25, 1902.

Application filed September 11, 1902. Serial No. 122,948. (No model.)

To all whom it may concern:

Be it known that I, WALTER THOMAS, a citizen of the United States, and a resident of Palatka, in the county of Putnam and State of Florida, have invented a new and Improved Trick-Sword, of which the following is a full, clear, and exact description.

This invention relates to a device for creating the deception of a sword thrust through a living person.

The device is useful in various connections, among the most important of which are in theatrical performances and advertising schemes.

15 This specification is an exact description of one example of my invention, while the claims define the actual scope thereof.

Reference is to be had to the accompanying drawings, forming a part of this specification, 20 in which similar characters of reference indicate corresponding parts in both the views.

Figure 1 is a plan view of the invention, and Fig. 2 is a detail section on the line 2 2 of Fig. 1.

25 The sword-blade is divided into two sections, (designated *a* and *b* in the drawings.) The section *a* is pointed at its outer end, and the section *b* carries a handle *c*. These sections *a* and *b* are separated from each other 30 for a distance equal, approximately, to the thickness of a man's body, and connected rigidly to the inner ends of each section are curved arms *d* and *e*. These arms are slotted, as indicated at *f* in Fig. 1 in the drawings, and *g* indicates clamping-screws, which

35 pass through the slots and hold the arms *d* and *e* rigidly together. This arrangement also enables the sections *a* and *b* of the blade to be adjusted toward and from each other, 40 so as to suit the size of the man to whom the device is to be applied. The arms *d* and *e* are formed each with two or more openings *d'* and *e'* therein, these openings being adapted to receive cords or like means for sustaining the device in position.

h indicates a rubber or other compressible

bulb, which is adapted to be filled with a red-colored liquid simulating blood. From this bulb *h* leads a tube *i*, which passes through an orifice *k*, formed in the pointed or end section *a* of the sword-blade. This orifice *k* may be located at the inner portion of the blade, as shown in the drawings, or at the end or point thereof, as desired.

In using the invention the device is adjusted under the clothing, so that the arms *d* and *e* lie snugly around the body, this adjustment being effected by the screws *g*, as explained. The sections *a* and *b* of the sword are arranged to project outward at opposite 55 sides of the body, and the arms *d* and *e* being hidden by the clothing the impression is given that a sword is actually thrust through the body. The bulb *h* and tube *i* should be concealed under the clothing, and by pressing the bulb the red-colored liquid therein may be forced out to simulate a bleeding wound. Suitable cords should be attached to the arms *d* and *e* through the holes *d'* and *e'* and these cords passed up to the shoulder 60 or shoulders, so as to support the arms *d* and *e* in proper place.

Various changes in the form, proportions, and minor details of my invention may be resorted to without departing from the spirit 75 and scope thereof. Hence I consider myself entitled to all such variations as may lie within the scope of my claims.

Having thus described my invention, I claim as new and desire to secure by Letters 80 Patent—

1. A trick-sword, comprising two blade-sections, and curved arms connected respectively with said sections and adjustably connected with each other.

2. A trick-sword, comprising two blade-sections, and means forming a rigid connection between said sections, such means curving sidewise to pass around one side of the body of the user.

3. A trick-sword, comprising two blade-sections, rigid arms connected respectively with

said sections, the arms being curved to meet each other at one side, and means for adjustably connecting the arms together.

4. The combination with a trick-sword, of
5 a flexible tube leading to a part thereof, and
means for forcing a liquid through the said
tube.

5. The combination with a trick-sword, of
a flexible tube leading to a part thereof, and
10 means for forcing a liquid through the said

tube, said means comprising a collapsible bulb communicating with the tube and containing the liquid.

In testimony whereof I have signed my name to this specification in the presence of 15 two subscribing witnesses.

WALTER THOMAS.
